UNITED STATES PATENT OFFICE.

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE.

DIAPHRAGM-FACE-PLATE BUFFER MECHANISM.

Application filed June 22, 1926. Serial No. 117,847.

Upper buffer mechanisms are used to keep the diaphragm face plates of adjacent passenger train cars in contact under all service conditions. The face plate must be permitted to move longitudinally, laterally and/or obliquely relative to its normal position on the car. It must be permitted to move laterally of itself (i. e., longitudinally of the car) to accommodate the draft gear movements and must move longitudinally of itself so that when one car swings more than its adjacent car the friction between the face plates will not tear either of them from their attachments. Furthermore, the face plate must move obliquely when the cars are moving on a curved track. The face plate may, of course, make all of these movements consecutively or simultaneously.

My invention relates to devices which yieldingly permit the face plate to make such movements and which have a tendency to return the face plate to its normal position and which do return it to such normal position when permitted to do so.

An object of the invention is to provide such a device which is simple and economical to manufacture and apply and which can be installed, inspected, repaired or replaced without entering the car or removing any part thereof, not even the diaphragm or its face plate. Furthermore, the device is noiseless because all the parts are under pressure contact.

In the drawings:

Fig. 1 shows a typical application of my device to a railway car.

Figs. 2, 3, 4 and 5 are diagrams showing the device in various service conditions.

Fig. 6 is a detail of the resilient member.

Fig. 7 is a detail of the car end attachment.

Fig. 8 is a detail of the face plate attachment.

Fig. 9 is a detail of the modified form of face plate attachment.

Figs. 10, 11, 12 and 13 are modified forms of springs.

The usual parts of a railway passenger train car are shown, such as the end wall 1, diaphragm 2 and diaphragm face plate 3.

My device comprises two resilient members 4, preferably duplicates, each of which has one of its ends pivotally secured to the end wall 1 by brackets 5 which are positioned equidistant from the center of the

car. The opposite end of each spring is pivotally secured to the face plate 3 by a device 6 which is positioned at the middle of the face plate. The inner ends of the springs may be secured to the end wall if desired, but the drawings illustrate the preferred form.

Fig. 1 shows a typical application of my device to a railway car, while Figs. 2-5, inclusive, are diagrams showing its action under service conditions. Fig. 2 shows the associated parts in normal position, while Fig. 3 shows them under maximum compression forcing the opposite ends of the spring toward each other or foreshortening it. Fig. 4 shows the device when the face plate has moved longitudinally (or sidewise of the car), wherein the opposite ends of one spring 7 are forced toward each other and the ends of the other spring 8 are pulled apart. Fig. 5 shows the face plate moved obliquely, wherein the springs have been foreshortened, as the distances between 9 and 10 and 11 and 12, respectively, are less than when in normal position, as shown in Fig. 2.

A stop 60 prevents the pivoted connections of the inner ends of the springs from going nearer to the end wall than the pivoted connections of the outer ends (or beyond dead center). If such a relation of parts should exist the device would not return to normal position.

The device may be applied to a car having an apexed diaphragm face plate with its middle portion higher than the place of attachment of the springs to the end wall.

The resilient member 4 must be capable of yieldingly foreshortening its length and also be capable of yieldingly increasing its length and then returning to its normal length under either condition by its own inherent power. Figs. 4, 10, 11, 12 and 13 show various types of resilient members which have this capacity. Fig. 4 shows a rectangular bar slightly bowed, while Figs. 10 and 12 are also rectangular bars bent to form an ogee or reverse curve. Fig. 13 shows a semi-elliptic spring with the auxiliary leaves on the inside of the curvature so as to resist the further deflection. Fig. 11 shows a member having a coil (or coils) to resist further deflection.

The resilient members are preferably bowed or given an initial deflection to assure that under further stress they will de-

flect in the desired direction. This is desirable, no matter what kind of spring is used. Furthermore, the bow makes an easier acting spring by giving it an initial eccentricity. 5 The spring must not be restricted in its action by contact with any part of the car, such as the face plate at 15 or 16 (or the car if the springs are bowed the other way). In the construction illustrated the axis 17 10 of the pivots of the connections of the bowed spring to the face plate are spaced apart from the face plate sufficiently to permit the spring to deflect under the maximum service conditions without interference with the face plate. The two bowed springs are interposed between the car end wall element 1 and the diaphragm face plate element 3 and, broadly expressed, the effective end of the spring adjacent the element toward which 20 the spring is bowed, must be spaced apart from that element to assure clearance for the proper action of the bowed spring. The "effective end" (20) is that portion of the spring where the deflection starts and is not necessarily its extremity.

The thrust longitudinally of the spring member, due to its resistance to buckling, is transmitted to the car wall and face plate, respectively, by the attachments 5 and 6, 30 which attachments must also provide a pivoted connection for the respective ends of the springs so that the spring is free to deflect independently of its attachments. It is desirable to transmit these longitudinal thrusts to the end wall and face plate substantially independent of the pivot means. This is accomplished by providing a bracket 5 having oppositely disposed perforated (21) walls 22 and 23 and a bolt 24 passing 40 through these perforations which also passes through an eye 25 formed on the end of the spring. The bracket 5 also has an abutment 26 and the eye 25 of the spring is made sufficiently larger than the bolt 24 to permit 45 the end of the spring to engage the abutment. Fig. 9 shows a bracket having elongated perforations 27 which could be used to assure the end of the spring engaging the abutment and, furthermore, to permit the spring (8) to move a certain distance before stressed, or an elongated eye could be used on the spring for the same purpose. A similar device 6 is shown for attaching the opposite end of the spring member to the face plate 3. The spring members are easily removed by simply taking out the bolts 24 at the opposite ends of the particular spring without disturbing the other spring.

The springs are made so that it is necessary to slightly shorten their length (by deflecting them) in order to install them, which causes the parts to be in pressure contact. This prevents rattling and noise which is desirable in sleeping cars and when 65 the particular device is on the rear end of

the last car, or when the car is coupled to a car not equipped with a face plate.

I claim:

1. In a railway car; the combination of an end wall, a diaphragm face plate, and two resilient members, each of said members having one of its ends pivotally secured to said end wall and its opposite end pivotally secured to said plate. 70

2. In a railway car; the combination of an end wall, a diaphragm face plate, and two resilient members, each of said members having its inner end pivotally secured to said end wall, and its outer end pivotally secured to said face plate. 80

3. In a railway car; the combination of an end wall, a diaphragm face plate, and two bowed spring members, each of said members having one of its ends pivotally secured to said end wall and its opposite end pivotally secured to said face plate. 85

4. In a railway car; the combination of an end wall, a diaphragm face plate, and two bowed spring members, each of said members having one of its ends pivotally secured to said end wall and its opposite end pivotally secured to said face plate, the pivoted connections of the bowed springs to the face plate being spaced apart therefrom sufficiently to permit the bowed spring to deflect under maximum service conditions without interference with the face plate. 95

5. In a railway car; the combination of an end wall element, a diaphragm face plate element, and two bowed spring members, each of said members having one of its ends pivotally secured to said end wall, and its opposite end pivotally secured to said face plate, the pivoted connections of the bowed springs adjacent the element toward which the spring is bowed being spaced apart therefrom sufficiently to permit the bowed spring to deflect under maximum service conditions without interference with the said element. 100

6. In a railway car; the combination of an end wall element, a diaphragm face plate element, and two bowed spring members, each of said members having one of its ends pivotally secured to said end wall, and its opposite end pivotally secured to said face plate, the effective ends of the bowed springs adjacent the element toward which the spring is bowed being spaced apart therefrom sufficiently to permit the bowed spring to deflect under maximum service conditions without interference with the said element. 110

7. In a railway car; the combination of an end wall element, a diaphragm face plate element, two bowed spring members, each of said members having one of its ends pivotally secured to said end wall, and its opposite end pivotally secured to said face plate, the pivoted connections of the bowed springs adjacent the element toward which the 125

5 spring is bowed being spaced apart therefrom sufficiently to permit the bowed spring to deflect under maximum service conditions without interference with said element, and a stop to restrict the lateral movement of the face plate.

10 8. In a railway car; the combination of an end wall, a diaphragm face plate, two resilient members, each of said members having one of its ends pivotally secured to said end wall, and its opposite end pivotally secured to said face plate, and a stop to restrict the lateral movement of the face plate.

15 9. In a railway car; the combination of an end wall element, a diaphragm face plate element, and two bowed spring members, each attached to both of said elements so as to foreshorten when the face plate moves out of normal position, the effective ends of the 20 bowed springs adjacent the element toward which the spring is bowed being spaced apart therefrom sufficiently to permit the bowed spring to deflect under maximum service conditions without interference with the said element.

25 10. In a railway car; the combination of an end wall, a diaphragm face plate, a device secured to said face plate adjacent its middle, two spaced apart brackets secured to the end wall, two resilient members, each having its inner end pivotally engaging said device, and its outer end pivotally engaging said bracket, and means to secure said members to said brackets which permit the longitudinal thrust of the member to be transmitted to the bracket.

30 11. In a railway car; the combination of an end wall, a diaphragm face plate, a device secured to said face plate adjacent its middle, two spaced apart brackets secured to the end wall, two resilient members, each having its inner end pivotally engaging said device, and its outer end pivotally engaging said bracket, and means to secure said members to said brackets and to said device, respectively, which permit the longitudinal thrust of the member to be transmitted to the bracket and to said device, respectively.

35 12. In a railway car; the combination of an end wall element, a diaphragm face plate element, a device secured to one of said elements, two spaced apart brackets secured to the other of said elements, two resilient members, each having one of its ends pivotally engaging said device, and its opposite end pivotally engaging said bracket, and means to secure said members to said brackets and to said device, respectively,

40 which permit the longitudinal thrust of the member to be transmitted to the bracket and to said device, respectively.

45 13. In a railway car; the combination of an end wall element, a diaphragm face plate element movable longitudinally, laterally or obliquely from its normal position, two spaced apart brackets secured to one of said elements, each having an abutment and oppositely disposed perforated walls, a device secured to the other of said elements having an abutment and oppositely disposed perforated walls, two bowed spring members, each of said members having one of its ends engaging an abutment on a bracket and its opposite end engaging the abutment on the device, and bolts pivotally securing said members to the device and brackets, respectively, by passing through the perforations and eyes formed on the ends of the members.

50 14. In a railway car; the combination of an end wall element, a diaphragm face plate element movable longitudinally, laterally or obliquely from its normal position, two spaced apart brackets secured to one of said elements, each having an abutment and oppositely disposed perforated walls, two bowed spring members, each of said members having one of its ends engaging an abutment on a bracket, and its opposite end pivotally secured to the other element, and bolts pivotally securing said members to the device by passing through the perforations and eyes formed on the ends of the members.

55 15. In an upper buffer mechanism for railway passenger train cars, a connection between a resilient member and a part of the car, said connection comprising a bracket having an abutment and oppositely disposed perforated walls, a resilient member having an eye formed at one end, and a bolt passing through said perforations and said eye, the size of said eye being sufficiently larger than the size of the bolt to permit the member to engage the abutment.

60 16. In an upper buffer mechanism for railway passenger train cars, a connection between a member and a part of the car, said connection comprising a bracket having an abutment and oppositely disposed perforated walls, a member having an eye formed at one end, and a bolt passing through said perforations and said eyes, the size of said eye being sufficiently larger than the size of the bolt to permit the member to engage the abutment.

ARTHUR E. SMALL.
